Primary Examiner — Karen S Acker*Assistant Examiner* — Wendy Arminio(74) *Attorney, Agent, or Firm* — Daniel J. Layden; Brandon J. Lee(57) **CLAIM**

The ornamental design for a film with embossing pattern, as shown and described.

DESCRIPTION

The sole FIGURE is a plan view of a film with embossing pattern showing my new design.

The broken line border surrounding the design depicts the boundaries of the claim and forms no part thereof.
